JOURNAL BOX

Harry J. Horn, Lansing, Mich., assignor to Motor Wheel Corporation, Lansing, Mich., a corporation of Michigan

Application August 10, 1936, Serial No. 95,084

7 Claims. (Cl. 308—47)

This invention relates to journal boxes, and more particularly to a novel construction and arrangement of the parts of a lid assembly for a journal box.

The lid assembly includes a cover for the journal box opening having an articulated connection with a hood pivotally mounted upon the journal box, a spring and lever arrangement for maintaining the cover in either its open or closed position, and a hood cap which is pivotally connected to the journal box.

Among the novel features of the present invention are the particular spring and lever arrangement, the construction of the hood and the manner in which it is mounted upon the journal box, and the arrangement of the parts whereby the lid structure may be readily mounted and demounted as a unit.

Other novel features of the present invention include the provision of a keeper bar utilized in maintaining the parts of the lid construction in assembled relation during mounting and demounting, and the provision of a pintle so arranged with respect to the parts of the lid construction as to be locked in position when the cover is mounted upon the journal box.

The principal objects of the invention reside in the provision of the novel features referred to above. Other objects more or less incidental and ancillary thereto will appear from the following description and the accompanying drawings wherein—

Figure 1 is an elevational view of a journal box lid constructed in accordance with one embodiment of the invention and showing the same applied to a journal box;

Figure 2 is a vertical sectional view taken on the line 2—2 of Figure 1 and looking in the direction indicated;

Figure 3 is a fragmentary vertical sectional view similar to that of Figure 2 but showing the hood cap in open position and the keeper bar operatively associated with the parts;

Figure 4 is a view similar to that of Figure 3 but showing the lid structure in raised or open position;

Figure 5 is a top plan view of the keeper bar;

Figure 6 is a side elevational view of the keeper bar;

Figure 7 is a fragmentary sectional view showing a modified form of the pintle; and

Figure 8 is a view similar to that of Figure 7 but showing still another modified form of the pintle.

Referring now to the drawing, a journal box 10 diagrammatically illustrated in dotted lines, is provided upon its roof or top wall with a hinge lug 11 having a cam surface 12 thereon and provided with an opening forming a bearing surface

13 for a pintle 14 upon which the lid structure is hinged.

The lid comprises a cover 16 shaped to coincide with the opening 17 of the journal box and may be provided with a gasket 18 riveted or otherwise secured adjacent the outer edge thereof. The cover 16 is provided with a raised central portion 19 to which a hood 21 is secured by a single universal connection 22 of any desired form to permit limited relative movement between the cover and the hood so that the cover will evenly engage the edges of the opening 17 preventing the entrance of dirt and water. The hood 21 is formed with sides 20 embracing the hinge lug 11 which have openings 25 to receive the pintle 14.

The mechanism for maintaining the lid in either open or closed position comprises a lever 23 pivoted at its lower end to the sides 20 of the hood 21 in any suitable manner as at 24 and formed at its upper end with a drawn portion 26 over which is positioned a compression spring 27 extending between the lever and the hood 21 where it is positioned around another drawn portion 28 formed thereon.

From the construction thus far described, it will be apparent that the compression spring 27 will urge the lever 23 into constant engagement with the cam 12. When the lid is in closed position it will be retained in that position by the action of the spring forcing the lever 23 against the flat face 29 of the cam, and when the lid is raised the lever will ride over the high point of the cam and maintain the lid in open position as shown in Figure 4. The effectiveness of spring 27 is increased by arranging it so that the lever contacts cam 12 in a region between spring 27 and pivot 24.

It is desirable that means be provided for adequately covering the upper open end of the hood and at the same time to provide for ready access to the spring 27 and lever 23 for inspection and servicing. It is also important that the entire lid structure be arranged so that it may be quickly and readily removed for replacement or servicing. To this end a hood cap 31 is pivotally secured, as indicated at 32, to the upper portions of the side walls 20 of the hood 21. It is provided with a flanged portion 33 extending downwardly over the front face of the hood 21 and releasably secured thereto by a screw 34 having a lock washer 35 between the head thereof and the face 33 of the hood cap. The screw 34 may be conveniently threaded into the drawn portion 28 of the hood.

The hood cap 31 is provided with means for locking the pintle 14 in place when the hood cap is in its closed position. This consists in a pair of downwardly extending ears 30 located at the opposite sides of the hood. The ears are located on the outside of the hood 21 and adjacent the

opposite ends of the pintle 14 when the cover is in its closed position as indicated in Figure 2. The ears 30 may be moved away from the ends of the pintle 14 so as to permit the removal of the pintle by rotating the hood cap 31 to the positions shown in Figures 3 and 4.

Of course the spring 27 positioned between the hood 21 and the lever 23 exerts a constant pressure against the hood 21 and through the connection of the hood and the pintle 14 provides a frictional engagement between the pintle, the lug and the sides 20 of the hood 21. Provision is made for releasing this frictional engagement in order to facilitate the removal of the pintle 14 after the hood cap has been rotated to the positions shown in Figures 3 and 4. This is accomplished by the use of a keeper bar 36. The bar has end portions 37 adapted to engage the remote faces of the hood 21 and the lever 23 adjacent the spring 27 when the cover is in its open position, as shown in Figure 4. When in that position the spring 27 is compressed sufficiently to permit the installation of the keeper bar 36 as shown in Figure 4.

When the cover is moved to its closed position with the keeper bar installed as just described the keeper bar constrains the assembly consisting of the hood 21, the lever 23 and the spring 27 to such extent that the lever does not contact the face 29 of cam 11. Consequently, all pressure is released from pintle 14 and the pintle may be readily removed from the lug 11. After the pintle has been thus removed the lid assembly including the cover 16, the hood 21, the lever 23 and the spring 27, may be removed from the journal box as a unit.

In the modified embodiment of the invention shown in Figure 7 the pintle 38 may be reduced in diameter at the ends thereof as at 39 forming shoulders 41. As shown in Figure 8 the pintle 45 may be similarly reduced in diameter a slight distance from the ends thereof as at 42 forming a pair of spaced shoulders 43 and 44 at each end. When the parts in these modified embodiments are in assembled position the action of the spring 27 will tend to move the hood 21 outwardly, causing the edges of hood 21 about the openings 25 to engage the reduced portions 39 of the pintle 38 or the reduced portion 42 of pintle 45. The shoulders 41, 43 and 44 thus serve to lock the respective pintles in position to prevent longitudinal movement thereof. When the lever, hood and spring are constrained by the keeper bar 36, the shoulders may be disengaged from the hood sides 20 and the pintle readily removed.

In Figures 7 and 8 the hood cap 31 is shown as being provided with the ears 30 as in the preferred embodiment of Figures 1 to 4, but it will be apparent that the ears are not essential when the pintle is provided with the reduced portions 39 or 42.

It will be understood that various modifications in construction and design may be made without departing from the spirit or scope of the invention as defined by the appended claims.

I claim:

1. In a lid structure for a journal box having a hinge lug, a cover, a hood secured to the cover, a pintle pivotally securing the hood to said hinge lug, a hood cap pivotally secured to the hood, means on said hood cap embracing said pintle when said hood cap is closed and arranged to free said pintle for ready removal when said hood cap is in open position.

2. In a lid structure for a journal box having a hinge lug, a cover, a hood secured to the cover and having an open top, a pintle pivotally securing the hood to the hinge lug, a hood cap pivotally secured to the hood, said hood cap including side portions arranged to engage the ends of said pintle when the hood cap is in closed position and to disengage said ends when the hood cap is in open position.

3. In a lid structure for a journal box having a hinge lug, a cover, a hood secured to the cover and having an open top, a pintle pivotally securing said hood to said hinge lug, and a hood cap pivotally secured to the hood, the hood cap including projections adjacent the pivotal axis thereof embracing the ends of said pintle when the hood cap is in closed position and adapted to free said ends for ready removal when the hood cap is in open position.

4. The combination with a lid structure for a journal box including a hood pivotally connected to the journal box and having an open top, a hood cap for closing said open top, a lever pivotally connected to the hood, and a spring positioned between the lever and the hood urging the lever against the journal box, of means for holding the hood lever and spring under stress to facilitate the removal of the lid structure as a unit from the journal box.

5. The combination with a lid structure for a journal box including a hood pivotally connected to the journal box and having an open top, a hood cap for closing said open top, a lever pivotally connected to the hood, and a spring positioned between the lever and the hood urging the lever against the journal box, of a keeper bar adapted to hold the hood and the lever in assembled relation to each other with the spring under stress therebetween to permit the removal of the lid structure from the journal box as a unit.

6. In a lid structure for a journal box having a hinge lug, a cover, a hood secured to said cover and provided with a side wall having an opening therein forming a bearing surface, and spring means between said hood and said journal box, a pintle pivotally securing said hood to said hinge lug and extending through said opening, said pintle having a reduced portion at one end thereof forming a pair of shoulders one at each side of said reduced portion, adapted to engage one side or the other of said hood side wall adjacent said opening, said reduced portion being maintained in engagement with said bearing surface by the action of said spring.

7. A journal box including, in combination, a hinge lug having a cam surface, a lid structure pivotally connected to said hinge lug and adapted to be moved to open and closed positions, said lid structure including a hood having an open top, a hood cap for closing said open top movably connected thereto, a lever pivotally connected to said hood and a spring interposed between the lever and the lid to urge the lever against said cam surface, the extent of compression of said spring being different for the open and closed positions, and means for engaging the lid structure and the lever when the spring is in its most compressed position to hold the spring in that position whereby the lid structure, lever and spring may be removed from the journal box as a unit.

HARRY J. HORN.
